A. H. REED

PUMP CONSTRUCTION

Filed May 24, 1922

UNITED STATES PATENT OFFICE.

ANDREW H. REED, OF FULLERTON, CALIFORNIA.

PUMP CONSTRUCTION.

Application filed May 24, 1922. Serial No. 563,210.

To all whom it may concern:

Be it known that I, ANDREW H. REED, a citizen of the United States, residing at Fullerton, in the county of Orange and State 5 of California, have invented a new and useful Pump Construction, of which the following is a specification.

This invention relates to pump construction, and an object of the invention is to 10 prevent the sanding up of pumps.

The accompanying drawings illustrate the invention:

Figure 1 is an elevation, partly in mid section, of a pump embodying the invention. 15 Fig. 2 is an enlarged longitudinal section of the lower portion of Figure 1.

Fig. 3 is a plan section on the line indicated by 3-3, Fig. 2.

Fig. 4 is an elevation, partly in section, 20 of the valve guide.

A working barrel is indicated at 5 and fitting inside thereof is the pump plunger 6. The working barrel 5 is provided at its lower end with a working barrel coupling 7 provided with a valve seat 8, in which is mounted a standing valve 9. Connected with the coupling 7 is a perforated pipe 10, to the lower end of which is attached a valve cage 11 provided with openings 12. To the lower end of the valve cage 11 is screw-threaded a valve stem guide 13 which preferably projects at 14 above the lower ends of the openings 12. The projecting portion 14 is preferably of frusto conical shape so that sand will readily slide therefrom. The guide 13 is provided at its axis with a bore 15 in which is slidably mounted the stem 16 of a valve 17. The valve 17 is preferably hemispherical and opens downwardly from the port 18, which it normally closes, so that when the valve is open sand will readily discharge through said port.

Surrounding the stem 16 between the 45 guide 13 and the valve 17 is a coil spring 19 of relatively low expansive power, the tension of said spring being preferably just sufficient to close the valve when the fluid pressures on opposite sides of the valve are equal. A comparatively small increase of fluid pressure above the valve over that below the valve is sufficient to open said valve against the pressure of the spring 19.

Connected with the standing valve 9 is a tube 20, commonly known as the pump an-

chor. The lower end of the anchor 20 is 55 spaced from the valve 17.

Assuming that the plunger 6 is being reciprocated in a well known manner to pump fluid from the well, the invention operates as follows:

The liquid being pumped enters the pipe 10 through its perforations 21 and, on the up-stroke of the plunger 6, said liquid passes through the standing valve 9 into the working barrel 5. During this up stroke of the plunger the liquid pressures are equal above and below the valve 17 and, therefore, the spring 19 will serve to hold the valve 17 closed. By reason of this the pipe 10 and tube 20 constitute a gas trap to minimize 60 the flow of gas into the working barrel, when the pump is installed in an oil well. In the ordinary pump construction, the lower end of the pipe 10 is closed permanently by a plug so that oil can enter the 65 pipe 10 only at the upper portion thereof through the perforations.

It will be understood that the valve 9 remains open, not only while the plunger is 70 making its up-stroke but also during a relatively short movement of the plunger at the beginning of its down-stroke. Until the pressure beneath the lower plunger valve, not shown, is sufficient to open said valve 75 against the pressure of the liquid above it, the column of liquid between the lower plunger valve and the valve 17 will function the same as a rigid rod to push open the valve 17 so as to permit any sand that may have 80 collected above the valve 17 to discharge from the pipe 10 through the port 18. Thus, 85 at the beginning of each down stroke of the plunger, the valve 17 will open to permit sand to discharge, consequently preventing sand from accumulating in the pipe 10 to such a height as to sand up the pump, as occurs when the lower end of the pipe 10 is 90 permanently closed by a plug in the customary manner, due to the sand plugging the lower end of the tube 20.

If it be not desired that the valve 17 open upon each down stroke of the plunger, the spring 19 will be made of sufficient strength to prevent said valve being opened by the 95 difference between liquid pressures on opposite sides thereof, as produced by operation of the plunger as described above. If the 100 stronger spring is employed, the sand that

2
5 accumulates on the valve 17 will be discharged from the pipe 10 at suitable intervals by raising the plunger 6 above the working barrel, thus permitting the weight of
10 the entire liquid column in the pump tubing to be imposed upon the valve 17. This weight being in excess of the combined pressures of the liquid outside of the pump and the spring 18 will cause the valve 17 to open,
15 thus permitting the sand to discharge. Then the pump plunger will be lowered into the working barrel and the pumping operation continued until it is again desired to discharge sand from the pipe 10.

15 I claim:

20 1. In a pump construction, the combination with the standing valve thereof, of a perforated pipe connected with the standing valve, a valve cage connected with the lower end of the perforated pipe and having openings in its side and having a port communicating with the pipe, a valve stem guide connected with the valve cage and having an upwardly tapering portion projecting above
25 the lower ends of the valve cage openings,

there being a bore at the axis of the valve stem guide, a valve to close the port and opening downward therefrom and having a stem slidably fitting the bore of the guide, and a spring surrounding the valve stem between the guide and valve.

2. In a pump construction, the combination with the standing valve thereof, of a perforated pipe connected with the standing valve, a valve cage connected with the lower end of the perforated pipe and having openings in its side and having a port communicating with the pipe, a valve stem guide connected with the valve cage and having an upwardly tapering portion projecting above
30 the lower ends of the valve cage openings, there being a bore at the axis of the valve stem guide, a hemispherical valve to close the port and opening downward therefrom and having a stem slidably fitting the bore of the guide, and a spring surrounding the valve stem between the guide and valve.

35 Signed at Los Angeles, California, this
16th day of May, 1922.

40 ANDREW H. REED.
